UNITED STATES PATENT OFFICE.

LEON MANN, OF NEW YORK, N. Y.

DESIGN FOR A RACK FOR UMBRELLAS AND OTHER ARTICLES.

43,246.

Specification for Design.

Patented Nov. 12, 1912.

Application filed September 7, 1912. Serial No. 719,250. Term of patent 3½ years.

To all whom it may concern:

Be it known that I, LEON MANN, a citizen of the United States of America, and a resident of the borough of Manhattan, in the county of New York, city and State of New York, have invented a certain new, original, and ornamental Design for a Rack for Umbrellas and other Articles, of which the following is a specification.

In the accompanying drawing, Figure 1 is a plan view of a rack illustrating the design; Fig. 2 is a front edge view of the same.

I claim:

The ornamental design for a rack for umbrellas and other articles as shown.

LEON MANN.

Witnesses:

A. C. McDONNELL,
EDNA A. MORELAND.
